LIFE RAFT OR FLOAT

Jesse L. Justice, Huntington Park, Calif., assignor
to L. A. Young Spring & Wire Corporation, De-
troit, Mich.

Application June 8, 1944, Serial No. 539,251

10 Claims. (Cl. 9—11)

1

The main objects of this invention are:

First, to provide a life raft or float which comprises a buoyant body having sealed water-tight compartments for the storage of water, food or equipment.

Second, to provide a structure of this character in which these compartments are provided with closures on both horizontal sides thereof so that they are accessible with the raft body either side up.

Third, to provide a lift raft or float in which the body portion is formed of metal and comprises a plurality of independent water-tight compartments providing a large degree of buoyancy in proportion to the size of the structure and substantial buoyancy even though several of the compartments may be punctured as by machine gun fire.

Fourth, to provide a life raft having these advantages which is very strong and rigid and capable of withstanding the shocks incident to use, such as dropping the raft a considerable distance as from a vessel.

Fifth, to provide a structure of this character in which there are no protuberances or projections likely to injure the occupants or to be broken off in use or handling.

Objects pertaining to details and economies of the invention will definitely appear from the description to follow. The invention is defined in the claims.

A structure which embodies the features of the invention is clearly illustrated in the accompanying drawing, in which:

Fig. 1 is a fragmentary plan view of a commercial embodiment of the invention, certain parts being partially in horizontal section and certain parts being shown by dotted lines.

Fig. 2 is a fragmentary side elevation with the deck suspended.

Fig. 3 is an enlarged longitudinal section on a line corresponding to line 3—3 of Fig. 1 with one of the cross members partially open.

Fig. 4 is an enlarged fragmentary section on line 4—4 of Fig. 3 showing structural details.

Fig. 5 is an enlarged elevation view showing details of the deck suspending neck.

Fig. 6 is an enlarged fragmentary section illustrating certain steps of manufacture.

Fig. 7 is an enlarged fragmentary view partially in horizontal section illustrating details of the means for attaching the deck suspending means to the float body.

Fig. 8 is a fragmentary view partially in horizontal section illustrating a modified form or em-

2

bodiment of my invention in which the float body is of elliptical shape having rounded ends as distinguished from the polygonal shape shown in Fig. 1.

5 Fig. 9 is an enlarged transverse section on line 9—9 of Fig. 8.

Fig. 10 is an enlarged fragmentary view of one of the metal body sections of the embodiment shown in Fig. 8.

10 Fig. 11 is a diagrammatic view illustrating the nesting of a plurality of rafts.

In the embodiment of the invention illustrated in Figs. 1 to 7, inclusive, the raft or float body is octagonal in shape while that shown in Fig. 8 15 is of elliptical shape. Each shape has certain advantages in structure and manufacture which will be brought out in the description.

The embodiment of the invention shown in Figs. 1 to 7 comprises side members 1, 1, end members 2, 2 and corner members 3. Each body member is formed of a plurality of tubular sheet metal or pipe sections 4 and 5, the sections being brought end to end and welded to each other and to the transverse partition elements 6, the 25 weld being indicated at 7, Fig. 3. These transverse partition members 6 constitute reinforcing members and bulkheads. It will be noted that the side and end corner members have mitered ends which are likewise welded together and 30 welded to the flat partition members 8 which constitute reinforcing members and bulkheads. The frame-like body is thus essentially tubular in cross section and is provided with a plurality of spaced bulkheads which result in a plurality of 35 water-tight compartments.

Each compartment is preferably provided with a pipe fitting 9 welded at 10 with the outer end of the fitting substantially flush or projecting but little from the surface of the body as shown in

40 Fig. 4. These fittings have removable plugs 11 which may be removed for testing each compartment and also for the internal coating of the compartment with a rustproof coating or finish. As shown in Fig. 3, the sections 5 are essentially

45 the same as the sections 4 except that the sections 5 have openings 12 preferably in both horizontal sides thereof, the openings receiving the cupped closure housings 13, the outer edges of which are welded as at 14 to the edges of the opening 12 forming a shield and rigid joint at this point.

The closure 15 which is provided with a suitable gasket is mounted on a suitable arm 16 pivoted at 17 on the ear 18 and detachably secured as 50 by means of the pin 19 to the opposed ears 20.

The closure is carried by the screw 21 which permits the adjustment of the closure into close sealing engagement. This provides a compartment 22 for storage of water, food or equipment. It will be noted that the closure housing is of such depth or is recessed to such an extent that the closure lies entirely within the plane of the sides of the body and is thus protected from injury and there are no projecting parts on which the occupants of the raft are likely to be injured.

The deck 23 is formed of slats and is of such dimensions as to pass through the frame-like body so that it is immaterial which side up the body may land, and the storage compartments are accessible from both sides of the frame. The deck is suspended by a net-like hanger designated generally by the numeral 24 made up of a plurality of strands 25 which, instead of being secured together by knots or weaving, are secured by means of clips 26. These clips 26 are formed of loops of wire, the legs of the loops being connected by the bight 27 and retained in spaced relation, the legs thereby constituting clips or links 28 which are clamped around the strands as shown in Fig. 5. It will be noted that each strand is clipped to the adjacent strands alternately (Fig. 2), thus providing a mesh-like structure. It is of advantage both from the standpoint of manufacture and the finished structure to secure the strands or ropes together by means of clips as there is no possibility of slipping knots between the strands, and in the event of injury to a strand the suspending net can be readily repaired. This may be done by an unskilled person.

The deck suspending net is secured to the inner side of the buoyant frame by means of the rings 29 which are pivotally secured to the body by means of the clips 30 which are welded at 31, as shown in Figs. 1 and 7. By securing the attaching means in this manner they can collapse against the side of the body, minimizing the likelihood of an occupant of the raft being injured if thrown against the same. It also facilitates the ready passage of the cable member along the top edge of net horizontally through the rings 29 as shown in Figs. 1 and 7. Similar attaching rings 32 are provided on the outside of the float body by means of the clips 33 as attaching means for the life lines 34, 35, the life lines 34 having floats 36 thereon as shown in Fig. 1.

Another point to be mentioned is that by thus attaching the rings 29 and 32 they are much less likely to be broken off than would be the case if they were rigidly secured.

In the embodiment of the invention shown in Figs. 8, 9 and 10 the frame-like buoyant body is of general elliptical shape and comprises side members 37, end members 371 and curved corner members 38. In this embodiment the side members are formed of a plurality of sections 39 of general bucket shape, as shown in Fig. 10, formed of drawn metal, the closed end or bottom portions 40 of these sections 39 being joined to the side walls by curved portions 41. This permits slight nesting as shown in Fig. 8, the open edges of the sections being welded at 42 so that the end portions 40 of the sections constitute bulkheads and reinforcing members.

The corner members 38 of the float body are formed of trough-like members 43 preferably stamped or drawn up from sheet metal and having narrow longitudinal flanges 44 on the longitudinal edges. The plate-like partition members 45 are arranged with their edges between these flanges and the parts are secured together by

welding at 46. These members 45 constitute bulkheads as well as reinforcing members. The end portions 47 of these corner members are disposed within the tubular end members 371 and welded thereto at 48. The opposite ends 49 are disposed within and welded to the adjacent sections 39 as indicated at 50. This provides a rigid frame-like float body and one in which the water-tight compartments are easily formed. The compartments 10 are provided with the pipe fittings 9 as described and certain of the compartments are provided with closure frames and closures adapting them as storage compartments, the same as previously described. The deck and its suspending and attaching means are also as above described.

It has been pointed out that the closure plugs 11 permit testing of the compartments as by means of air pressure, but it is also important that they provide means for the application of a suitable rust resistant or rust retarding material to the inside of the compartment walls. Since it is not possible to paint the walls before welding this is an important feature of the invention. A rust-proof external finish is also provided which includes the canvas wrapping 51 which is shown as spirally wound around the buoyant body. To properly protect the metal it is given an external coating of rust-proof or rust resisting paint. The paint is then covered with a lacquer and the canvas is applied by means of a rubber cement. The lacquer protects the paint from the deleterious action of the rubber cement. The canvas is coated with water-proofing and mold retarding material. This results in very effective protection for the metal as well as a covering for the metal. It will be understood that exposed metal might become unduly heated or objectionably cold. This covering overcomes both objections.

It will be understood that these life rafts or floats are commonly made in varying sizes, for example, in sizes designed to carry 55, 35, 20 and 15 persons. By making them of polygonal and elliptical shapes the different sizes may be nested as illustrated. In Fig. 11 a 35 size octagonal float is nested within a 55 size, and the 15 and 20 size floats are nested within each other in the octagonal floats.

The invention is here illustrated and described in two practical embodiments thereof. No attempt has been made to illustrate or describe other embodiments or adaptations as it is believed this disclosure will enable those skilled in the art to embody the invention as may be desired.

It is again pointed out that the structure is economical to produce, has a high degree of buoyancy, is not destroyed by fire as is the case with wood floats and rafts, is comparatively light in weight and at the same time strong and rigid, being capable of withstanding the shocks incident to dropping into the water from a vessel. It is immaterial which side up the raft falls as the deck adjusts itself and the storage compartments are accessible from both sides. With the bulkheads constituting reinforcing members the structure may be formed of comparatively light gage metal and still possess the requisite strength.

Having thus described the invention what is claimed as new and desired to secure by Letters Patent is:

1. In a life raft or float, the combination of a frame-like buoyant body comprising side and end corner body members, each body member comprising a plurality of tubular sheet metal sections disposed end to end, flanged bulkheads between the sections, the flange of a bulkhead telescop-

5

ingly engaging within the end of one section and the adjoining end of an adjacent section, the adjacent edges of the sections being welded to each other and to the flanges of said bulkheads, the side and end corner body members having mitered joints, and flat bulkheads disposed at such mitered joints, the adjacent edges of the body members at said mitered joints being welded to each other and to said last named bulkheads, such assembly providing a plurality of water-tight compartments.

2. In a life raft or float, the combination of a frame-like buoyant body comprising side and end corner body members, each body member comprising a plurality of tubular sheet metal sections disposed end to end, bulkheads between the sections, the bulkheads having a flange telescopingly engaging within the end of one section and the adjoining end of an adjacent section, the adjacent edges of the sections being welded to each other and to the flanges of said bulkheads, the side and end corner body members having mitered joints, and bulkheads disposed at such mitered joints, the adjacent edges of the body members at said mitered joints being welded to each other and to said last named bulkheads, such assembly providing a plurality of water-tight compartments.

3. In a life raft or float, the combination of a frame-like buoyant body comprising a plurality of tubular metal sections disposed end to end, bulkheads at the joints of the sections, the adjacent edges of the sections being welded to each other and to said bulkheads, the bulkheads providing a plurality of water-tight compartments, a decking provided with a suspending net, attaching rings for said net, and horizontally disposed elongated clips welded at their opposite ends to said sections, said clips providing vertically disposed openings for receiving said rings, said net including a cable member disposed along the top edge of the net and extending horizontally through said rings.

4. In a life raft or float, the combination of a frame-like buoyant body comprising a plurality of tubular metal sections disposed end to end, bulkheads between the sections, the adjacent edges of the sections being connected to each other and to said bulkheads, the bulkheads providing a plurality of water-tight compartments, and a rustproof covering for said body, said covering comprising successively from said body outwardly, a coat of rust resisting paint, a coat of lacquer, a coat of rubber cement and a wrapping of canvas, said canvas being wrapped spirally longitudinally of the body and across the abutting ends of the tubular metal sections of the body.

5. In a life raft or float, the combination of a frame-like buoyant body comprising side members and corner members, said side members including a plurality of tubular metal sections disposed end to end, and bulkheads between the sections, the adjacent edges of the sections being connected to each other and to said bulkheads, the bulkheads providing a plurality of water-tight compartments, said corner members being formed of upper and lower opposed trough-like metal stampings having flanges along the adjacent edges thereof, horizontal plate-like members disposed between said flanges and connected thereto providing reinforcing members and bulkheads, said corner members telescopingly engaging within the adjoining open ends of the tubular sections of the side members and constituting bulkheads for the last named tubular sections.

6. In a life raft or float, the combination of a frame-like buoyant body comprising a plurality

6

of tubular sheet metal sections disposed end to end and joined by welded joints and having sheet metal transverse members at the joints welded at the joints and constituting reinforcing members and bulkheads providing a plurality of water-tight compartments, a decking provided with a suspending net, attaching rings for said suspending net, and horizontally disposed elongated clips welded at their opposite ends to said sections, said clips providing vertically disposed openings for receiving said rings, said net including a cable member disposed along the top edge of the net and extending horizontally through said rings.

7. In a life raft or float, the combination of a frame-like buoyant body comprising side members and corner members, said side members including a plurality of tubular sections disposed end to end and joined by welded joints and having sheet metal transverse members at the joints and constituting reinforcing members and bulkheads providing a plurality of water-tight compartments, said corner members being formed of upper and lower opposed trough-like metal stampings having flanges along the adjacent edges thereof, horizontal plate-like members disposed between said flanges and connected thereto providing reinforcing members and bulkheads, said corner members telescopingly engaging within the adjoining open ends of the tubular sections of the side members and constituting bulkheads for the last named tubular sections.

8. In a life raft or float, the combination of a frame-like buoyant body of tubular section formed of metal, a plurality of spaced bulkheads within said body providing a plurality of water-tight compartments, said bulkheads constituting reinforcing elements for said body, and a rust-proof covering for said body, said covering comprising successively from said body outwardly, a coat of rust resisting paint, a coat of lacquer, a coat of rubber cement and a wrapping of canvas.

9. In a life raft or float, the combination of a frame-like buoyant body, a deck, and a suspending net for said deck comprising a plurality of strands, each strand being alternately secured to adjacent strands to provide an open mesh by double ring wire clips, the rings of the clips being substantially spaced and being connected at one end by a eight-like cross portion which maintains the rings in spaced relation.

10. In a life raft or float, the combination of an elongated frame-like buoyant body of tubular section comprising side, end and corner members, the side members comprising a plurality of bucket-like metal sections, the closed end of one section being disposed within the open end of the adjacent section, the sections being welded together at the joints thereof, the closed end portions of the sections constituting reinforcing members and bulkheads, the corner members being formed of opposed trough-like metal stampings having out-turned flanges at the edges thereof, longitudinal members disposed between such flanged edges and welded thereto providing reinforcing members and bulkheads, and annular end members disposed between and welded to the adjacent ends of said corner members, the opposite ends of the corner members being welded to adjacent sections of the side members, the ends of the corner members constituting abutment members, the several parts coacting to provide a plurality of water-tight compartments.

JESSE L. JUSTICE.
